UNITED STATES PATENT OFFICE.

LESLIE B. GRAHAM, OF EAST CHICAGO, INDIANA.

CONDENSER FOR BOILER-WASHING SYSTEMS.

Application filed October 17, 1919. Serial No. 331,284.

To all whom it may concern:

Be it known that I, LESLIE B. GRAHAM, a citizen of the United States, residing at East Chicago, in the county of Lake and 5 State of Indiana, have invented certain new and useful Improvements in Condensers for Boiler-Washing Systems, of which the following is a specification.

In boiler washing systems in which, for 10 the sake of conserving heat and water, the products blown off from a locomotive boiler are separated into steam to be condensed for reuse in refilling the boiler, water that is accumulated for use in washing out the 15 boiler previous to refilling, and sludge or precipitate that is discharged into the sewer, the practice has been introduced, prior to my present invention, of trapping the blown-off products (steam, water, and 20 sludge) in a separator, and incorporating a spray condenser in the system in a manner to receive steam or vapor from the separator and the inherent heat of such products, with a flow superinduced by the sub-atmospheric 25 environment produced by the condenser, and deliver the water of condensation from the condenser to the filling tank of the system, spray-water, for condensing purposes, being automatically released to the condenser as 30 it is needed by means of a thermostat influenced by the arrival of steam in the condenser. It has also been proposed heretofore to deliver steam from the blown-off products to a surface condenser, the cooling 35 medium for which is water supplied under control of a valve which is operated by the pressure or weight of blown-off products. But in the former of these methods, condensation starts only after evaporation has 40 continued for some while, and then only when the pressure of evaporating steam is sufficient to force it into the condenser, while in both methods the condensing operation is dependent upon a condition which may 45 terminate before the process of evaporation has fully ended.

The present invention has for one of its objects to provide for control of the spray water by means more directly responsive to 50 the presence, within reach of the condenser, of blown-off products having the capacity to give off vapor or steam, with the advantage, among others, of not only getting prompt action in the spray-nozzle even at relatively 55 low temperature, but prolonging the action of the nozzle after the principal volume of

steam has been condensed and so long as there is present hot water to give off vapor; and also to develop an improved mechanical control, and one independent of thermodynamics.

A further object is to provide means for regulating at will the time of interruption of the condensing spray after the delivery of blow-off water has ceased, and thereby insuring recovery of a greater proportion of the remanent steam in the blow-off pipe after the boiler pressure has lowered.

Accordingly, the primary feature of the present invention consists in providing the 70 spray-water valve, in a system of the kind described, with a control that is directly responsive to the presence of blow-off water in the separator; one subordinate feature incident to this primary feature consisting in 75 the combination with the spray-water valve of a controlling means, for instance, a float lever, water ball, and hydrostatic device that is responsive to water level in the separator; and another subordinate feature consisting 80 in means for regulating the discharge of water from the separator, and thereby prolonging the time, after blow-off water ceases to arrive, during which a body of blow-off water will be detained in the separator or other receptacle and utilized to hold open the spray valve, with the advantage of drawing remanent steam from the blow-off pipe or elsewhere in the system where it is permitted to linger by the then 85 reduced pressure of the boiler.

In the accompanying drawing, in which one embodiment of the invention is shown by way of illustration—

Figure 1 is a schematic view of that portion of a blow-off, washout, and refilling system for boilers with which the present invention is immediately concerned; and

Figure 2 is a detail view of the separator with one embodiment of spray-valve controlling element therein.

1 represents the pipe through which water is blown off from a boiler; 2 the separator into which it is delivered under the boiler pressure and from which sludge may be discharged by opening valve 2^a; 3 the washout tank receiving water from the separator through the pipe 4; and 5 the filling tank that receives from the condenser 6 water accumulating in the latter from the spray-nozzle 7 and condensation, by the spray, of steam that flows through cross-over pipe 8

from the separator 2. These elements are not of my invention and may follow previously invented lines, including the means for controlling delivery of spray-water to 5 nozzle 7, namely, the valve 9.

Valve 9 has heretofore been controlled automatically in a manner to deliver spray-water only when there is steam to be condensed, namely, by means of a thermostatic 10 actuator subject to heat effect of steam entering the condenser.

According to the present invention, valve 9 is controlled by the blowoff water; this is 15 preferably by such water after reaching the separator 2, and through the medium of some convenient water-level actuated device of which various kinds are known, but which in the present illustration is a lever 10 fulcrumed at 11, connected by rod 12 with 20 valve-lever 13, and under control of the float 14 within the separator. Baffle 15 protects the float from impact of incoming water and leaves the float free to act.

Valve 2^a being closed, blowoff water 25 delivered through pipe 1 will accumulate in separator 2 up to the level of overflow pipe 4, and thereby raise the float 14 and open spray-water valve 9. This positively insures action of the spray, and insures it more 30 promptly than when subjected to the delivery of blowoff water indirectly through the medium of rising steam and a thermostat influenced thereby. Moreover, the spraying action will be insured and the 35 drawing of vapor into the condenser by the vacuum of condensation will be continued after the incoming steam has ceased to have the volume necessary to maintain valve-actuating pressure in the thermostat. Consequently, the present arrangement causes 40 delivery of a greater number of heat units and a greater volume of refilling water into the filling tank.

After the blowoff has ceased, the water 45 accumulated below over-flow pipe 4 will escape through drain pipe 16 and permit the float to settle and cut off flow of spray water. But drain pipe 16, besides being of such 50 relatively small capacity as not to materially affect water accumulation in separator 2 under the large delivery of blowoff pipe 1, may have a regulating valve 17 to control its draining effect, especially after the arrival of blowoff water has ceased, and thus 55 measure the time during which the water level will continue to support float 14 in valve opening position, and consequently the time during which condenser action will 60 continue. The importance of this arises from the fact that after blowoff water ceases to flow there still remains in the system a considerable volume of steam or vapor which will be drawn through the cross-over pipe 65 by the vacuum of condensation if the action of the spray be continued.

The present invention, therefore, not only provides means independent of the condenser action to control the spray and renders such means directly responsive to the blowoff water and continues so long as such water remains present, but provides means controlling the pressure of the water and renders the same adjustable at will. 70

I claim:

1. In combination with a hot water system, a receptacle receiving hot water, a condenser connected to receive vapor arising from the water in said receptacle, means in said receptacle for controlling the admission of water to said condenser that is in turn controlled by water in said receptacle and continues under control thereof during the presence of said water therein, and means for effecting a delayed discharge of 75 water from the receptacle. 80

2. In combination with a hot water system, a receptacle into which hot water is delivered by the system, a condenser connected to receive vapor arising from the water delivered to said receptacle, means in said receptacle for controlling the admission of water to said condenser that is in turn controlled by the level of water in said receptacle and continues under the control 90 thereof during the presence of said water, and means for effecting a release of the water from said receptacle, that is of less capacity than the delivery capacity of the 95 system. 100

3. In combination with a hot water system, a receptacle receiving water therefrom, a condenser connected to receive vapor arising from the water delivered to said receptacle, a water supply for said condenser, a controlling means for said water supply 105 that is in turn controlled by the level of water in said receptacle and continues under control thereof during the presence of said water, and controllable means for gradually releasing said water. 110

4. In a hot water delivery system, a condenser for vapor arising from water delivered thereby, a receptacle connected to receive water delivered by said system, and deliver vapor therefrom to said condenser, means controlling the level of water in said receptacle, and a control for the condenser that is subject to the level of the water in 115 said receptacle. 120

5. In a hot water delivery system, a condenser for vapor arising from water delivered thereby, a receptacle receiving water delivered by said system, and a control for the condenser that is subject to the level of the water in said receptacle; said receptacle having an outlet that limits the level of water therein to a level at which the condenser is continued in action. 125

6. In a hot water delivery system, a condenser for vapor arising from water deliv- 130

ered thereby, a receptacle receiving water delivered by said system, and a control for the condenser that is subject to the level of water in said receptacle; said receptacle 5 having an outlet that limits the level of water therein to a level at which the condenser is continued in action, and a drain of less capacity than that of the water delivered by the system and which is adapted, 10 when the delivery of water is reduced, to lower the level of water in the receptacle to that at which the condenser is arrested. 7. In a hot water delivery system, the combination of a condenser for vapor arising 15 from water delivered thereby, a receptacle receiving water delivered by said system, and a control for the condenser that is subject to the level of water in said receptacle; said receptacle having an outlet that 20 limits the level of water therein to a level at which the condenser is continued in action, and a drain of less capacity than that of the water delivered by the system and which is adapted, when the delivery of 25 water is reduced, to lower the level of water in the receptacle to that at which the

condenser is arrested; said drain having an adjustable valve for determining the time required to arrest the condenser.

8. In a boiler washing system, a separator 30 having a blowoff pipe through which it receives blowoff water and having an overflow for water accumulating therein, a condenser receiving vapor from said separator, a spray for said condenser, a water 35 level actuated controlling means for said spray subject to the level of water in the separator, and a drain for said condenser of less capacity than the blowoff pipe.

9. A blow off and refilling system for 40 boilers, comprising means for receiving and separating the blown off products from the boiler, a condenser connected to receive the vapor of said blown off products, means 45 operated by a part of the blown off products for controlling the admission of condensing water to the condenser, and means for gradually terminating the action of said controlling means.

Signed at East Chicago, Indiana, this 50
4th day of Oct., 1919.

LESLIE B. GRAHAM.
